UNITED STATES PATENT OFFICE.

HARRY B. WHITE, OF CANTON, OHIO, ASSIGNOR, BY MESNE ASSIGNMENTS, TO AUTO SPECIALTIES MANUFACTURING CO., OF SAN FRANCISCO, CALIFORNIA, A CORPORATION OF CALIFORNIA.

BOW REST AND CLAMPING DEVICE.

1,381,853.

Specification of Letters Patent. Patented June 14, 1921.

Application filed February 15, 1917. Serial No. 148,754.

To all whom it may concern:

Be it known that I, HARRY B. WHITE, a citizen of the United States, residing at Canton, in the county of Stark and State of Ohio, have invented a new and useful Bow Rest and Clamping Device, of which the following is a specification.

My invention relates particularly to bow-supporting and clamping devices adapted for use in connection with vehicle tops, and especially automobile tops.

The primary object of the invention is to provide a device of the character indicated which is of such construction and operation as to enable the top bows to be readily entered in the device in the operation of clashing the top, but which is nevertheless capable of clamping the bows with facility and security, rattling of the top and of the parts of the device itself being wholly obviated.

A further object is to provide a device of the character indicated with improved body-attaching means, whereby the device may be attached with great facility and the utmost security to an automobile body.

In the preferred embodiment of the invention, I employ a fixed, or body-attached, vertical stock having its upper end equipped at its rear side with a recessed resilient bearing; a bow-clamping member having its lower end pivotally connected with the lower end of said stock; and a clamping lever pivotally connected with the upper end portion of said bow clamping member and equipped with a stock-engaging member, preferably a link, adapted to engage said bearing. Thus, when the devices on opposite sides of the automobile body are open, the bows of the top may be lowered into them, the upper ends of the fixed stocks being free from obstruction, so that the bows will slip freely into the spaces provided for them.

The invention is illustrated, in its preferred embodiment, in the accompanying drawings, in which—

Figure 1 is an elevational view (partly in section) of a bow rest and clamping device embodying the invention, the device being shown in the clamping position.

Fig. 2 is an edge elevation of the same.

Fig. 3 is a side elevation of the device showing the same in the opened position.

Fig. 4 is a section on the line 4—4, Fig. 1.

Fig. 5 is a detail perspective view of the attaching stud.

Similar numerals of reference indicate corresponding parts throughout the several figures of the drawings.

Referring more especially to the construction illustrated in the accompanying drawings, the numeral 1 indicates the fixed stock which is preferably channel shaped in cross section, although any other suitable design of stock may be used, said stock being provided with an attaching socket 2 arranged to receive the extremity of the usual drop iron or bracket 3, which is provided upon the side of the vehicle body, a stud 4 being located through the channel 5, which connects with the under side of the socket 2, and is located transversely thereto, said stud being provided with the inclined upper surface 6 arranged to engage the under face of the bracket or drop iron 3. A reduced screw 7 is provided upon the stud 6, a washer 8 being located over said reduced extremity and a nut 9 engaged thereon to draw the stud tightly into engagement with the bracket or drop iron in order to retain the stock thereon.

The lower extremity of the stock 1 is curved as shown at 10 and an ear 11 is formed thereon for the purpose of connecting the hinged clamping arm 12, which is provided with a pair of spaced ears 13, a pin 14 passing through said ears and through the ear 11 forming a hinged connection between the stock and the clamping arm.

The clamping arm is preferably cast in any suitable cross section and is provided with the upper and lower bow engaging projections 15 and 16, respectively, a rest 17 being formed upon the lower extremity of said clamping arm for the purpose of receiving the lowermost bow. The upper extremity of the clamping arm is turned inwardly as shown at 18 and provided with a reduced projection 19 arranged to enter the aperture 20 formed through the wall of the stock 1, a pad 21 of leather, rubber or other suitable material being provided along the inner face of the clamping arm to prevent marring or scratching the bows by contact therewith.

A spring 22, preferably formed of heavy wire, is carried in the upper portion of the

channel shaped stock 1, said spring resting intermediate its extremities in the recess 23 formed in the transverse web 24, the lower extremity of said spring being bent inwardly as indicated at 25 and located in a socket 26 formed in the stock, said spring being held rigidly in place within said socket. The upper extremity of the spring above the web 24 is free and terminates beneath the upper web 27 formed upon the stock, notches 28 being formed in the side flanges of the channel shaped stock adjacent the upper extremity of the spring.

The operating lever 29 is pivoted, by means of a pin 30, to an ear 31 formed upon the upper edge of the inturned portion 18 of the clamping arm, thus pivotally connecting said lever to the upper extremity of the clamping arm. A link 32 preferably cast and comprising the curved arms 33 and the connecting bar 34 as shown in the drawings is pivotally connected near to the upper extremity of the lever 29 at a point adjacent the pivotal point of said lever by means of a pin 35 or its equivalent. When it is desired to clamp the bows within the device the clamping arm 12 is moved into the open position as shown in Fig. 3 of the drawings. The bows are then lowered in the usual manner, the lowermost bow resting upon the rest member 17 and the clamping arm is then moved toward the fixed stock 1, the projection 19 upon said clamping arm being received within the aperture 20 in the fixed stock, guiding the upper end of the clamping arm and limiting the clamping movement thereof. The tie bar 34 of the link is received within the notches 28 of the stock and the lever 29 is moved into the clamping position shown in Fig. 1, the link 32 being opposed by the spring 22 as the clamping lever is moved into the clamped position affording a firm and positive clamping action and preventing any rattling of the device when clamped. The upper and lower projections 15 and 16 engage the upper and lower bows respectively as the clamping action takes place.

It will be understood from Fig. 3 that the upper end portion of the stock 1 is free from projecting movable parts, so that the bows of the top will, when the top is being clashed, slip freely down into the space between the stock 1 and the bow-clamping member 12. The recess 28 and the spring 22 afford, in effect, a resilient bearing which is open at the rear side, that is at the side which is next to the automobile body. Thus, the bearing for the portion 34 of the stock 1 engaging member 33 will yield, as shown in Fig. 1, when the lever 29 is thrown to the clamping or pressure-applying position. This arrangement effectively prevents the possibility of rattling, and the projection 15 above the recess 28 prevents the possibility

of the link 33 becoming disengaged from its bearing. By preference, the recess is provided in the stock, instead of in the spring, as it is thus easier to give greater prominence to the projection above the recess, thereby adding to the security.

In constructions now in use, it is common to mount upon the upper end of the fixed stock a clamping lever for securing the bow-clamping member in the closed position. In such constructions, the movable securing member interferes with the passage of the upper end of the stock inside of the bows of the top, this difficulty being enhanced by the cover or fabric attached to the bows. The improved construction obviates this difficulty, and at the same time provides adequately to prevent rattling either of the bows or of the parts of the bow-supporting and clamping device.

Although the drawings and above specification disclose the best mode in which I have contemplated embodying my invention I desire to be not limited to the details of such disclosure, for, in the further practical application of my invention, many changes in the form and construction may be made, as circumstances require or experience suggests, without departing from the spirit of the invention within the scope of the appended claims.

I claim:

1. A device of the character described, comprising a stock arranged to be attached to a vehicle body, a spring located near one extremity of said stock, an arm hinged to the other extremity of said stock, a clamping lever pivotally mounted upon the free end of said arm, a spacing member carried by the upper extremity of said arm and arranged to engage said stock and a link carried by said lever and arranged to engage the spring upon said stock, said lever and link arranged to draw said arm toward said stock to clamp the bows of a top therebetween.

2. A device of the character described comprising a stock arranged to be attached to a vehicle body, the upper extremity of said stock being of channel form and provided with a transversely disposed notch, a spring carried within said upper end of the stock, an arm hinged to the lower extremity of the stock, a spacing member carried by the free extremity of said arm and arranged to engage said stock, a clamping lever pivotally mounted upon the free extremity of said arm and a link carried by said lever and arranged to engage the notch in said stock and contact with said spring, said lever and link arranged to draw said arm toward said stock to clamp the bows of a top therebetween.

3. In a device of the character described, the combination of a stock equipped with

means for attaching it to a vehicle body, and provided with a transverse notch near one extremity, a spring mounted upon said stock adjacent said notch, a clamping arm 5 hinged to the other extremity of the stock, an inturned portion provided upon the free end of said clamping arm and arranged to contact with the stock in the clamped position, a clamping lever pivotally mounted 10 adjacent the free end of said clamping arm and a link carried by said lever and arranged to be received within said notch and to contact with said spring, said lever and link arranged to draw said arm toward said 15 stock to clamp the bows of a top together.

4. In a device of the character described, the combination of a stock equipped with means for attaching it to a vehicle body, and provided with a transverse notch near 20 one extremity, a spring mounted upon said stock adjacent said notch, said stock provided with a socket near said spring, a clamping arm hinged to the other extremity of said stock, an inturned portion provided 25 upon the free end of said clamping arm, a projection provided upon said inturned portion and arranged to enter said socket when the parts are in the clamped position, a clamping lever pivotally mounted adjacent 30 the free end of said clamping arm and a link carried by said clamping lever and arranged to be received within said notch and to contact with said spring, said lever and link arranged to draw said arm toward 35 said stock to clamp the bows of a top together.

5. In a bow-supporting and clamping device, the combination of a vertical stock equipped with body-attaching means and 40 provided at the rear side of its upper end with a yielding bearing inclosed within the stock, a bow-clamping member having its lower end pivotally connected with the lower end of said stock, and a lever pivotally 45 mounted on the upper end of said bow-clamping member and equipped with a stock-engaging member adapted to engage said bearing.

6. In a bow-supporting and clamping device, the combination of a vertical stock equipped with body-attaching means and provided at the rear side of its upper end with a yielding bearing inclosed within the stock, a bow-clamping member having its 55 lower end pivotally connected with the lower end of said stock, a lever pivotally

mounted on the upper end of said bow-clamping member, and a link pivotally connected with said lever and provided at its free end with a member adapted to engage 60 said bearing.

7. In a bow-supporting and clamping device, the combination of a vertical stock equipped with body-attaching means and provided at its rear side of its upper end 65 with a yielding bearing, a bow-clamping member having its lower end pivotally connected with the lower end of said stock, a lever pivotally mounted on the upper end of said bow-clamping member, and a U- 70 form link having the ends of its arms pivotally connected with said lever and its webportion adapted to engage said bearing.

8. In a device of the character set forth, the combination of a vertical stock equipped 75 with body-attaching means and provided at the rear side of its upper end with a bearing having an overhanging projection, a spring substantially inclosed in the stock having its lower end anchored in said stock 80 and its upper portion crossing the space beneath said projection, a clamping member having its lower end pivotally connected with the lower end of said stock, a clamping lever having an inturned end pivotally 85 connected with the upper end portion of said clamping member, and a link pivotally connected with an intermediate portion of said lever and having a portion adapted to embrace the upper end of said stock and 90 engage said spring.

9. In a bow-supporting and clamping device, the combination of a vertical stock equipped with body-attaching means and provided at the rear side of its upper end 95 with a spring inclosing rearwardly open bearing, a spring in said bearing, a bow-clamping member having an inwardly curved lower end pivotally connected with the lower end of said stock and having an 100 inwardly turned upper end adapted to engage the upper end of said stock, a clamping lever having an inturned upper end pivotally connected with the inturned upper 105 end of said clamping member, and a link pivotally connected with said lever and having a free end portion adapted to embrace the upper end of said stock and engage said spring bearing.

In testimony that I claim the above, I 110 have hereunto subscribed my name.

HARRY B. WHITE.
